UNITED STATES PATENT OFFICE.

GEORGE B. GARDNER, OF HAVERHILL, MASSACHUSETTS, ASSIGNOR TO UNITED SHOE MACHINERY COMPANY, OF PATERSON, NEW JERSEY, A CORPORATION OF NEW JERSEY.

HEEL-PART SHOE-TURNING MACHINE.

1,125,506.

Specification of Letters Patent. Patented Jan. 19, 1915.

Application filed March 9, 1909, Serial No. 482,839. Renewed May 26, 1914. Serial No. 841,142.

To all whom it may concern:

Be it known that I, GEORGE B. GARDNER, of Haverhill, county of Essex, State of Massachusetts, have invented an Improvement in Heel-Part Shoe-Turning Machines, 5 of which the following is a specification.

This invention relates to certain improvements in machines for turning the heel portion of turn shoes which have been sewed 10 about the heel, and more particularly it relates to certain improvements in the heel-turning devices shown in my prior Patent 15 #797,802, dated August 22, 1905.

The heel turning device shown in said 20 prior patent comprises three depending turning fingers, which are adapted to extend into the shoe before it is turned, and a sole engaging head which is adapted to be moved between the fingers.

25 In said prior device the action of drawing the upper sharply about the ends of these fingers causes an excessive amount of friction between the upper and said fingers, particularly at the middle of the back of the 30 shoe, and, as the force required to overcome this friction and the force required to bend the upper, as it is turned, is all transmitted to the sole by the head, the strain placed on the upper and stitches is excessive and therefore objectionable.

The object of the present invention is to 35 improve the heel turning device of said prior patent, so as to relieve the strain upon the upper and stitches, and further to improve the machine of said patent so as to facilitate the turning operation. I accomplish 40 this object by the means shown in the accompanying drawing which illustrates the best form of the invention at present known to me.

In the drawing Figure 1 is a side elevation of a shoe turning machine provided 45 with my invention. Fig. 2 is a front view of the main operating parts of the machine. Figs. 3 and 4 are sectional views on the line 50 $a-a$ of Fig. 1, showing the parts in different positions. Figs. 5, 6 and 7 are enlarged sectional views on the line $b-b$ of Fig. 2, showing the parts in different positions. Fig. 8 is a detail sectional view on the line $c-c$ of Fig. 5. Fig. 9 is a detail view on the line $d-d$ of Fig. 5. Fig. 10 is a detail view of the front side of the main upper or

counter holding finger. Fig. 11 is an end view of said finger. Fig. 12 is a detail view, 55 partly in section, of the end portion of said finger. Fig. 13 is a detail sectional view, on an enlarged scale, taken at the line $e-e$ of Fig. 12. Fig. 14 is a detail sectional view on the line $f-f$ of Fig. 5. Fig. 15 is a plan 60 view of the sole-engaging head.

As shown in the drawing, the main frame 1 is provided with a boss 2, in which a rod 3 is adapted to reciprocate vertically, said rod having a head 4 on its upper end, the 65 upper side of which is provided with a sole-engaging face having teeth 4^a thereon adjacent the front edge thereof. Suitable means for raising and lowering said head may be provided, such as the means shown 70 in said prior patent, or the power driven means indicated in the drawing, which comprises a main shaft 5 having a crank 6 which is connected to a connecting rod 7, said rod 7 being connected to a lever 8 and said lever 75 8 being connected to the lower end of rod 3 by a link 9, so that when the shaft is rotated in the direction of the arrow in Fig. 1 said rod 3 will be lifted. A returning spring 10 for the shaft is indicated. 80

A standard 11 is mounted on the frame and a horizontally projecting bracket 12 is mounted thereon, said bracket extending forwardly and having its front end portion 12' obliquely disposed to the horizontal. A 85 turning finger 13 is pivotally connected by a pin 13° to the under side of said bracket end portion 12' and extends at an angle of about 45° to the perpendicular to within a short distance of the path of said head 4. 90 The pin 13° is arranged to permit a certain swinging movement of said finger 13, shoulders 13', 13'' on said finger, at its base, limiting the movement thereof on said pin in both directions. Said finger is normally 95 held by gravity in the position of Figs. 5 and 7, in which position the front shoulder 13' bears against the under side of said bracket 12. Said finger 13 is disposed to engage the heel portion of the upper at the 100 middle of the back thereof, and, as in my said prior patent, is provided with three antifriction rolls 14, 15 and 16, at its lower end. In my said prior patent, however, said rolls were shown as mounted to rotate about 105 the same axis, while in the present instance

- the end rolls are arranged to rotate about axes which are at an angle to the axis of the middle roll. With the arrangement of said prior patent, the ends of the side rolls 5 were pressed against the counter with much greater force than the sides thereof, thereby causing undue strain on such portions of the shoe and greatly increasing the difficulty of turning.
- 10 According to my present invention the end rolls are set at such an angle with relation to the middle roll that the longitudinal contour of the surfaces of said rolls follows approximately the normal curve of 15 the counter so that the strain, or friction, of the rolls on the counter is practically no greater at one point than at another, and the counter is not pulled out of shape or damaged. The manner in which these rolls 20 are preferably mounted on the end of the finger 13 may be described as follows. A pair of hangers 17 and 18 are provided, which are adapted to be set into slots in the end of the finger, and to be secured therein 25 by a pin 19. The side faces of said hangers are arranged obliquely with relation to each other and a pair of bearing pins 20 and 21 are fixed in said hangers, said pins having heads at the outer ends thereof and 30 being passed through the tapering rolls 14 and 16 before they are fixed in said hangers. The ends of the middle pin 22, on which roll 15 is mounted, are inserted in 35 recesses in the pivots 20 and 21, and when held in this position, the hangers are inserted in the slots and secured by pin 19. As it is desirable to provide for wide variations in sizes of the shoes, said hangers are 40 preferably mounted in an end piece 23 which is provided with arms 23', which are adapted to be removably secured in corresponding slots in the body of finger 13, so that other end pieces having rolls of different sizes may be attached.
- 45 A pair of depending fingers 24 and 25 are adjustably mounted in transversely extending horizontal slots in the under side of the bracket 12, said fingers extending convergently and terminating at some distance above the lower end of the finger 13. An adjusting screw 26 is swiveled in a lug 12^a on the lower side of bracket 12 and is provided with right and left screw threads at the opposite ends thereof, which are 55 screwed into said fingers 24 and 25 at their base portions, whereby said fingers may be adjusted toward and from each other, according to variations in the width of the shoes, by turning said screw 26.
- 60 An upper engaging device or dog 27 is mounted to slide on the outer or front side of the finger 13, in a longitudinal dovetail groove formed in said finger, as shown in Fig. 8. The lower side of said dog 27 is 65 provided with a concave upper engaging
- face 27^a, which extends obliquely upward from the inner side thereof, so that said face and the surface of said finger on which said dog is mounted are as nearly continuous as practicable, and then outwardly and 70 downwardly, as shown. A link 28 is connected by a pivot 29 at its lower end to the dog 27, and at its upper end by pivot 30 to the front end of a lever 31, the latter extending rearwardly through a slot 13^a, 75 formed through the middle portion of said finger 13, see Fig. 10, in an approximately horizontal direction, when in its normal position, said lever being located in and adapted to swing in the vertical plane midway 80 between said fingers 24 and 25. The lever 31 is pivoted at an intermediate point by pin 31' to the lower end of a rod 32, which is mounted to slide longitudinally in the bracket 12 in a position nearly parallel to 85 the finger 13, and in the vertical plane of said lever 31, said rod 32 being held in a depressed position by means of a pair of springs 33 which are connected to a stoppin 34 in the rod 32, and act to draw said 90 pin against the end of a guiding boss 12^c on the bracket 12 through which the rod passes. An operating finger 35 is mounted to slide in the bracket 12 in vertical alignment with the head 4, and also in the vertical plane of lever 31, said finger 35 depending approximately to the level of the friction rolls on the end of finger 13, and having sole-engaging teeth at its lower end which are disposed directly over the teeth 95 4^a of the head 4, closely adjacent the front edge thereof. Said finger 35 is provided with a slot 35^a at its middle portion, through which the lever 31 extends, see Fig. 9, so that, when said finger 35 is forced 100 upwardly, the end of said lever, which is engaged thereby, will be swung up and the opposite end will be moved down, causing the dog 27 to be forced down on finger 13. The pivot 31' is so located that the distance therefrom to the pivotal connection of 105 lever 31 with link 28 is somewhat longer than the distance therefrom to the points where said lever is engaged by the finger 35, so that the downward movement of said 110 dog 27 will be somewhat more rapid than the upward movement of the head 4, due allowance also being made for the fact that the movement of the dog is oblique to the lever 31, while the movement of the finger 115 35 is nearly perpendicular thereto. A shank supporting pair of springs 36 are connected to a stop pin 36' in the upper end of said finger 35 and are also connected to the bracket 12 so that said pin is normally held 120 thereby against the upper end of a guiding boss 12^a, through which said finger 35 passes.
- 125 A pair of turning fingers 37 and 38 are mounted to slide longitudinally in dovetail 130

grooves formed on the outer sides of said fingers 24 and 25, and said fingers 37 and 38 are connected at their upper ends, by means of links 39 and 39' to the outer ends 5 of levers 40 and 41, respectively, said levers 40 and 41 being pivoted at their middle portions upon links 42 and 43 respectively, the latter being pivotally mounted at their lower ends on the upper side of the bracket 12. The inner ends of said levers 40 and 41 are both pivotally connected to a head 44 on the upper end of a rod 45, said rod being mounted to slide vertically in the bracket 12 in the same vertical plane as that of the lever 31. The lower end of said rod 45 is provided with a head 45' and a spring 46 is interposed between said head and the under side of said bracket 12, so that said spring, acting against said head 45' will 20 draw the head 44 against the upper side of the bracket and hold the fingers 37 and 38 in such a position that the ends thereof are practically even with the ends of the fingers 24 and 25, as shown in Fig. 4.

25 A shank supporting arm 47 is adjustably mounted in a dovetail slot on the upper side of the head 4, and extends rearwardly therefrom in a slightly upwardly inclined direction. Preferably the inclination of the arm 30 is such that it extends approximately at right angles to the turning finger 13, thus assisting in supporting the shoe in its inclined working position hereinafter referred to. Said arm may be provided with an enlarged end portion 47' of somewhat greater 35 width than the shank portion thereof.

The operation of my device is substantially as follows:—A shoe which has been sewed about the heel inside out is placed 40 on the upper holding fingers 13, 24 and 25 with the middle of its heel portion at the outer side of the finger 13, and the shoe bottom extending obliquely upward at an angle of about 45° to the path of the head 45 4, in which position the lower ends of the fingers 24 and 25 touch the bottom of the sole, as indicated in Fig. 1. In this position the face 27^a of the dog 27 is held closely adjacent the upper edge of the heel portion of 50 the shoe upper, at the middle thereof and, preferably, so that the lip formed at the lower inner end of said face, or the portion next the finger 13, extends to a slight extent beneath said portion of the upper.

55 In turning the heel part of a shoe to the best advantage and with the least strain on the shoe, the first operation to be performed is to press the portion thereof at the point where the sole is joined to the upper inwardly in a line which approximately bisects the angle between the sole and the back of the counter. The head 4 is arranged to move so that its raised teeth will engage the shoe with the sole seam at the 60 middle of the back, and, as the shoe is held

with its bottom at about 45° to the path of said head, it will be apparent that when the head is raised it will press the seam inward approximately in the direction of said bisecting line. It is desirable that the front 79 edge of the head pass as closely as practicable to the rolls at the lower end of finger 13 on the up, or turning movement, but, with the device of said prior patent I have found that if the finger which corresponds to finger 13 is set as closely as desirable for the up movement of the head on the down movement the teeth on the head are liable to catch in the lining of the shoe and the counter is liable to become bound between 80 the head and the sides or rolls of the finger, with the result that the shoe is damaged. With my present construction the arrangement is such that when the finger 13 is swung upward to its fullest extent the space 85 between the rolls and the front side of the head will be just sufficient to permit the back of the shoe to be drawn therebetween, while when the finger has dropped back to its normal position the space therebetween 90 is much wider and sufficient to prevent all possibility of the shoe back being caught therebetween. In operation, when the head engages the seam and presses it inwardly the upward pressure immediately causes the 95 finger 13 to be swung upward and, therefore, its end to be swung toward the path of the head, and the finger will be held in this position during the remainder of the turning operation. When the operation is 100 finished, or as soon as the head begins to move downward, the finger 13 will swing back to its normal position by gravity, increasing the space between the rolls and the path of the plunger to the necessary extent. 105

A further advantage of the oblique arrangement of finger 13 to the path of the plunger is that there is no possibility of binding between the finger and the head after the latter has passed the rolls, but the principal 110 advantage of this arrangement is that it holds the shoe in the most advantageous position for turning.

When the head 4 is raised and the turning operation begun, by pressing the sole upwardly, as shown in Fig. 5, as soon as the sole is raised to an appreciable extent its upper side is pressed against the lower end of finger 35 causing the latter to be forced upwardly, so that it swings the lever 31 and 120 moves the dog 27 downwardly, into engagement with the edge portion of the upper. As the dog 27 is moved downwardly, it acts to push down the back of the counter portion of the shoe, and, as this movement is 125 slightly faster than the up movement of the head, it tends to push it down slightly faster than the head 4 tends to pull it up by forcing up the sole and drawing said counter portion about the friction rolls. By this 130

means the strain which must be placed on the upper by the head to draw the upper about the lower end of the finger 13, will be reduced to a minimum. In other words, 5 practically all the pull which must be necessarily exerted upon the upper, by means of the upward pressure on the sole, is a pull sufficient to bend the upper about the anti-friction rolls as it is drawn up between the 10 fingers. During the first part of this movement the portion of the upper which projects above the upper edge of the counter will be rolled outwardly, as indicated in Fig. 6, but as soon as the dog firmly engages the 15 upper edge of the counter the whole back part of the heel portion will be positively pushed down slightly faster than it would otherwise be drawn down by the head. This movement is continued until the dog 27 is 20 moved into engagement with the end of the dovetail groove in which it slides, as shown in Fig. 7, so that further upward movement of the finger 35, which would tend to move the dog below this point, will be permitted 25 by the yielding of the rod 32 against the action of its springs 33.

When the heel portion of the shoe is partially turned as shown in Fig. 6, the arm 47, which supports the sole in the shank portion 30 thereof, brings the sole into engagement with the head at the lower end of the sliding rod 45, and further upward movement of the head 4 causes said rod 45 to be forced upwardly, raising the inner ends of 35 the levers 40 and 41 and forcing downwardly the fingers 37 and 38. The supporting fingers 24 and 25 are set so that when the fingers 37 and 38 are forced downwardly, they will engage the upper adjacent the sole, and push it down as the sole 40 is pushed up by the head, causing the upper to be drawn about the ends of said fingers and thus turned. By this means the turning operation is performed to the best advantage with a minimum strain on the shoe, 45 that is, the middle of the counter portion is first pushed in and partly turned and then, as the turning of this portion of the shoe is finished, the sides of the counter portion 50 are quickly pushed down by fingers 37 and 38, the downward movement of said fingers making it unnecessary to raise the head beyond a point at which the turning operation 55 of the middle of the counter portion is complete. In this connection it will be observed that it is necessary to have the lower ends of the side fingers arranged to terminate at a much higher point than that of the middle finger, when in their normal position, to permit the shoe to be held in the inclined position of Fig. 1.

After the heel portion is turned, before 60 the head 4 is lowered, and while the sole is securely clamped against the head by the rods 35 and 45, the sole of the shoe may be

most conveniently bent across the ball, or "broken", as it is usually termed, preliminary to the turning operation of the fore part, as indicated in Fig. 7, the upper being drawn down so that the shoe is held in the bent position shown, in which position it may be conveniently transferred to the fore-part turning apparatus which is preferably operated in conjunction with the apparatus above described. 75

It will be understood that while the device may be operated most conveniently in the position shown, the terms "upwardly" and "downwardly," and terms of similar import, as used in the claims, are merely 80 relative.

Having thus described my invention, what I claim as new and desire to secure by Letters Patent is:—

1. In a shoe turning machine, turning devices comprising a sole-engaging means for the outer side of the sole and an upper bending device for engaging the inner side of the upper, before the shoe is turned, and means for pressing the upper toward the sole while the shoe is operated upon by said turning devices, substantially as described. 85

2. In a shoe turning machine, turning devices comprising a sole-engaging means for the outer side of the sole and an upper bending device for engaging the inner side of the upper, before the shoe is turned, and means for engaging the edge portion of the upper to press the same toward the sole while the shoe is operated upon by said turning devices, substantially as described. 95

3. A shoe-turning machine having heel-part turning devices comprising oppositely disposed sole-engaging and upper engaging devices relatively movable to draw the upper about said upper-engaging device and perform the turning operation, and means for pushing the upper in the direction in which it is drawn by said turning devices, substantially as described. 105

4. A shoe-turning machine comprising oppositely disposed and relatively movable heel-part turning devices and means, operating simultaneously therewith, for pressing the middle portion of the counter in the direction in which it is drawn by said turning devices, substantially as described. 115

5. A shoe turning machine having heel-part turning devices comprising oppositely disposed sole-engaging and upper engaging devices relatively movable to draw the upper about said upper-engaging device and perform the turning operation, and means for engaging the edge portion of the upper to force the same in the direction in which it is drawn by the action of said turning devices, substantially as described. 120

6. A shoe turning machine comprising a turning finger adapted to extend into the counter portion of the shoe, a sole-engaging 130

- device movable at one side of said finger and oppositely disposed thereto, an upper-engaging device movable longitudinally of the finger at the opposite side thereof to engage 5 the edge portion of the upper when the shoe is held in position for turning on said finger, means for moving said sole-engaging device to perform the turning operation, and means for simultaneously moving said upper engaging device toward the end of said finger, substantially as described.
7. A shoe turning machine comprising a turning finger adapted to be inserted in the counter portion of the shoe, and a sole engaging device and an upper engaging device simultaneously movable in opposite directions at opposite sides of said finger, substantially as described.
8. A shoe turning machine comprising a turning finger adapted to be inserted in the counter portion of the shoe, a sole-engaging device and an upper-engaging device movable at opposite sides of said finger, and means, operated by said sole-engaging device when moved in one direction, for moving said upper engaging device in the opposite direction, substantially as described.
9. A shoe turning machine comprising a turning finger adapted to be inserted in the counter portion of the shoe, a sole-engaging head movable at one side of said finger to perform the turning operation, an upper-engaging device movable longitudinally of said finger at the opposite side of said finger, and an operating device disposed to be actuated by said head, as it is moved to perform the turning operation, to move said engaging device toward the end of said finger, substantially as described.
10. A shoe turning machine comprising a turning finger adapted to be inserted in the counter-portion of the shoe, a sole-engaging head movable at one side of said finger, an upper engaging device mounted to slide longitudinally of said finger on the opposite side thereof from said head, and means for simultaneously moving said head and engaging device in opposite directions to perform the turning operation, substantially as described.
11. A shoe turning machine comprising a depending turning finger adapted to be inserted in the counter-portion of the shoe, a sole-engaging head vertically movable at one side of said finger, an upper engaging device movable longitudinally of said finger at the opposite side of said finger, a depending operating finger above said head and adapted to engage the upper side of the sole directly thereover, and connections between said upper engaging device and said operating finger for moving said upper engaging device downwardly, as the operating finger is raised by said head, substantially as described.
12. A shoe turning machine comprising a depending turning finger adapted to be inserted in the counter-portion of the shoe, a sole-engaging head vertically movable at one side of said finger, an upper engaging device mounted to slide longitudinally of said finger on the opposite side thereof from said head and having an upper engaging face on the lower side thereof, and means for simultaneously raising said head and lowering said engaging device, substantially as described.
13. A shoe turning machine comprising a depending turning finger adapted to be inserted in the counter-portion of the shoe, a sole engaging head vertically movable at one side of said finger, an upper engaging device mounted to slide longitudinally of said finger on the opposite side thereof from said head and having a concaved upper engaging face on the under side thereof extending from the side of said finger upwardly and outwardly, and means for simultaneously raising said head and lowering said engaging device, substantially as described.
14. A shoe turning machine comprising a turning finger and a sole engaging head oppositely disposed with relation thereto, and means for simultaneously moving said head and said finger in opposite directions, substantially as described.
15. A shoe turning machine comprising a turning finger and a sole engaging head oppositely disposed with relation thereto and movable longitudinally of said finger at one side thereof, and means operated by said head, as it is moved in one direction, for moving said finger in the opposite direction, substantially as described.
16. A shoe turning machine comprising a pair of turning fingers adapted to be inserted at opposite sides of the counter portion of the shoe, a sole engaging head disposed between said fingers, and means for simultaneously moving said fingers longitudinally in one direction and said head in the opposite direction, substantially as described.
17. A shoe turning machine comprising a pair of depending turning fingers adapted to be inserted at opposite sides of the counter-portion of a shoe, a vertically movable sole engaging head, and means operated by said head for moving said fingers downwardly as said head is raised, substantially as described.
18. A shoe turning machine comprising a pair of depending holding fingers adapted to be inserted at opposite sides of the counter-portion of a shoe, a turning finger extending longitudinally of each holding finger and slidably mounted thereon, a head, means for moving the same upwardly, and means for moving said turning fingers.

- downwardly during the upward movement of said head, substantially as described.
19. A shoe turning machine comprising a pair of depending turning fingers adapted to be inserted at opposite sides of the counter-portion of a shoe, a sole-engaging head vertically movable between said fingers, a rod depending in the path of said head, and connections between said rod and said fingers for moving said fingers downwardly as said rod is moved upwardly by said head, substantially as described.
20. A shoe turning machine comprising a pair of depending turning fingers adapted to be inserted at opposite sides of the counter-portion of a shoe, a sole-engaging head vertically movable between said fingers, means operated by said head for moving said fingers downwardly as said head is raised, and means permitting transverse adjustment of said fingers toward and from each other, substantially as described.
21. A shoe turning machine comprising a pair of depending holding fingers adapted to be inserted at opposite sides of the counter-portion of a shoe, a turning finger extending longitudinally of each holding finger and slidably mounted on the outer sides of said holding fingers, a head, means for moving the same upwardly, and means for moving said turning fingers downwardly during the upward movement of said head, substantially as described.
22. In a shoe turning machine having a turning finger adapted to be inserted in the shoe at the heel end thereof, a sole engaging device movable longitudinally of said finger to draw the heel portion of the shoe about the end thereof to turn the same, and a pair of anti-friction rolls disposed at the end of said finger and rotatable about axes lying at such an angle to the opposite sides of said finger that their longitudinal contour corresponds approximately to the curve of the counter of the shoe, substantially as described.
23. A shoe turning machine comprising a turning finger adapted to be inserted in the shoe at the heel end thereof and a sole-engaging head movable longitudinally of said finger to turn the heel-portion of the shoe, and a pair of tapering anti-friction rolls oppositely disposed at the end of said finger and mounted to rotate about axes extending at such an angle to each other that the longitudinal contour of the surfaces of said rolls corresponds approximately to the curve of the counter of the shoe, substantially as described.
24. A shoe turning machine comprising a depending turning finger adapted to be inserted in the counter portion of the shoe, a sole-engaging device upwardly movable at one side of said finger to draw the upper about the end of the finger at a certain speed, and an upper engaging device for forcing the upper down the opposite side of said finger at a somewhat greater speed, substantially as described.
25. A shoe turning machine comprising a depending turning finger adapted to be inserted in the counter portion of the shoe, a sole-engaging device upwardly movable at one side of said finger to draw the upper about the end of the finger, an upper engaging device, and means for operating the same by said sole-engaging device to force the upper down the opposite side of said finger at a faster speed than that at which it is drawn up by said sole-engaging device, substantially as described.
26. A shoe turning machine comprising a sole-engaging head, an oppositely disposed turning finger adapted to be inserted in the middle of the heel portion of the shoe and means for relatively moving said head and finger, said finger having its counter engaging portion extended obliquely toward the path of said movement in close proximity thereto to hold the shoe in position to be engaged adjacent the sole seam at the middle of the back end thereof whereby the engaged portion of the shoe may be pressed inwardly in a direction approximately midway between the back and bottom portions of the shoe, substantially as described.
27. A shoe turning machine comprising a vertically movable sole-engaging head, a turning finger adapted to be inserted in the middle of the heel-portion of the shoe, and having its counter engaging portion extending obliquely toward the path of said head in close proximity thereto, and a shank supporting portion on said head extending approximately at right angles to said finger, substantially as described.
28. A shoe turning machine comprising a vertically movable sole-engaging head, a turning finger adapted to be inserted in the middle of the heel portion of the shoe and having its counter engaging portion extending obliquely toward the path of said head in close proximity thereto, and a pair of depending fingers at the opposite side of said head from said turning finger, and terminating at a relatively higher elevation than the point at which the end of said turning finger is held, to engage the shoe bottom at points some distance from the heel end thereof, and hold the same in an inclined position with relation to the path of said head, substantially as described.
29. A shoe turning machine comprising a sole-engaging head, an oppositely disposed turning finger adapted to be inserted in the middle of the heel portion of the shoe means for relatively moving said head and finger, said finger having its counter engaging portion extended obliquely toward the path of said movement in close proximity thereto,

and an additional pair of fingers at the opposite side of said head from said turning finger, disposed to engage the shoe bottom adjacent the shank to coöperate with said turning finger to hold the shoe in position to be engaged adjacent the sole-seam at the middle of the back end thereof, whereby the engaged portion of the shoe may be pressed inwardly in a direction approximately mid-way between the back and bottom portions of the shoe, substantially as described.

30. In a shoe turning machine, the combination of a series of depending turning fingers, comprising a middle finger adapted to engage the middle of the counter portion of the shoe and two side fingers adapted to engage opposite sides thereof adjacent the shank, a sole-engaging head vertically movable between said fingers, an upper engaging device, means for moving said engaging device to force down the upper at the opposite side of said middle finger from said head during the preliminary portion of the turning movement, and means for moving said side fingers downwardly during the latter portion of said movement, substantially as described.

31. In a shoe-turning machine, the combination of a series of depending turning fingers comprising a middle finger adapted to engage the middle of the counter portion of the shoe and two side fingers adapted to engage opposite sides thereof adjacent the shank, a sole-engaging head vertically movable between said fingers, an upper engaging device, and means, operated by said head as it is moved upwardly, for moving said engaging device to force the upper downwardly at the opposite side of said middle finger from said head, and for moving said side fingers downwardly during the latter portion of the movement of said engaging device, substantially as described.

32. A shoe turning machine comprising a depending turning finger adapted to be inserted in the counter portion of the shoe, a sole-engaging device upwardly movable at one side of said finger to draw the upper about the end of the finger, and means permitting movement of said finger toward and from the path of said sole-engaging device, as and for the purpose set forth.

33. A shoe turning machine comprising a depending turning finger adapted to be inserted in the counter portion of the shoe, a sole-engaging device upwardly movable at one side of said finger to draw the upper about the end of the finger, means permitting said finger to be drawn by the turning action of said head toward the path thereof and to move away from said path at the end of said action and a stop for limiting the movement of said finger toward said path, substantially as described.

34. A shoe turning machine comprising a sole-engaging head movable in a predetermined path, a finger pivotally mounted at one end and extending obliquely to said path in proximity thereto, said finger being adapted to swing on its pivot toward and from said path to a limited extent, substantially as described. 70

35. In a shoe turning machine a pivotally supported turning finger adapted to be inserted in the counter portion of the shoe, and a sole-engaging device movable longitudinally of said finger to draw the counter portion about the end of said finger, said finger being adapted to swing on its pivot to carry the end portion thereof toward and from the path of said sole-engaging device, substantially as described. 75

36. A shoe turning machine comprising a depending turning finger adapted to engage the upper at the heel end of the shoe, a head adapted to engage the heel end of the sole having a shank supporting arm inclined to the surface of the head, and means to move said finger and head relatively, substantially as described. 80

37. A heel part turning finger for shoe turning machines adapted to be received within the counter portion of the shoe before the commencement of the turning operation having at its upper-engaging end a pair of antifriction rolls for engaging the upper along the heel seam rotatable about axes lying at such an angle to the opposite sides of said finger that their longitudinal 95 contour corresponds approximately to the curve of the counter of the shoe at the heel seam, substantially as described.

38. A heel part turning finger for shoe turning machines adapted to be received within the counter portion of the shoe before the commencement of the turning operation having at its upper-engaging end a pair of oppositely disposed tapering antifriction rolls for engaging the upper along 100 the heel seam mounted to rotate about axes at such an angle to each other that the longitudinal contour of the surfaces of said rolls corresponds approximately to the curve of the counter of the shoe at the heel 115 seam, substantially as described.

39. A heel part turning machine, having, in combination, a shoe supporting device, a turning finger adapted to be inserted in the counter portion of the shoe, means for relatively moving said device and finger to turn the upper, and means permitting a movement of said finger toward and from the back of the counter during the turning operation, substantially as described. 120

40. A heel part turning machine, having, in combination, means for clamping the heel end of the sole to support the shoe, a turning finger for engaging the shoe counter along the heel seam, pivotally mounted to 125 130

permit a movement toward and from the shoe supporting means, coöperating with said means, and means for relatively moving said shoe supporting means and finger 5 to turn the upper, substantially as described.

In testimony whereof, I have signed my

name to this specification, in the presence of two subscribing witnesses.

GEORGE B. GARDNER.

Witnesses:

L. H. HARRIMAN,

H. B. DAVIS.

Copies of this patent may be obtained for five cents each, by addressing the "Commissioner of Patents, Washington, D. C."

It is hereby certified that in Letters Patent No. 1,125,506, granted January 19, 1915, upon the application of George B. Gardner, of Haverhill, Massachusetts, for an improvement in "Heel-Part Shoe-Turning Machines," errors appear in the printed specification requiring correction as follows: Page 2, line 121, strike out the word "shank"; same page, line 122, strike out the word "supporting"; and that the said Letters Patent should be read with these corrections therein that the same may conform to the record of the case in the Patent Office.

Signed and sealed this 23rd day of February, A. D., 1915.

[SEAL.]

J. T. NEWTON,

Acting Commissioner of Patents.
